COAT

Joseph Siegel, New York, N. Y.

Application March 18, 1936, Serial No. 69,465

12 Claims. (Cl. 2-93)

My present invention, while primarily concerned with overcoats or topcoats, has a wide and varied field of usefulness in connection with coats and jackets of all types and relates particularly to the provision of improved means for permitting the wearer of a coat or jacket to gain ready access to the pockets of the garments worn under the coat without unbuttoning or otherwise opening the latter. The invention provides 10 a concealed opening in the coat which is normally closed by a metallic slide fastener.

Features of the invention are the provision of such a metallic-seam closed opening so arranged that the fastener is concealed from view both 15 from the outside and inside of the coat; in which the interengaging fastener teeth are fully protected by fabric so that no metal will contact the hands of the wearer of the coat where the fastener is arranged within the coat pocket, and 20 the disposition of the slide fastener in such a relationship to the coat that the coat will have no tendency to sag when the metallic seam is opened.

This construction is, of course, peculiarly well 25 suited for embodiments in outer garments of the type adapted to be worn outdoors in cold or inclement weather, such for instance as overcoats, topcoats, raincoats, windbreakers etc.

In accordance with one embodiment of the 30 invention a slit or opening with its associated fastener is diagonally disposed within a pocket of the coat preferably terminating above the bottom of the pocket so that gloves, cigarettes, matches, change or other small objects will not 35 fall out of the pocket when the slide fastener is opened. Preferably the teeth of the seam or "zipper" are covered by fabric flaps on the pocket side of the coat so that the hands of the wearer will not come into contact with the cold 40 metal of the seam. A special flap is arranged in the inside of the coat so that the metallic seam will not show when the inside of the coat is exposed. This flap serves the additional purpose of preventing the sack coat or other under- 45 garment of the wearer from becoming pinched in or torn by the interengaging teeth as the slide member is moved to close the slit. One advantage of the diagonal arrangement of the opening is the fact that the cloth of the coat 50 will not tend to sag when the seam is opened as would be the case were the seam horizontally disposed. Also the angle of the slit (running rearwardly and downwardly) facilitates the insertion of the hand through the slit without un- 55 natural bending of the wrist or arm.

In accordance with another embodiment of the invention, instead of placing the "zipper" closed slit within the pocket, a seemingly conventional patch pocket cooperates with the body of the coat to provide a recess just back of the pocket, and within this recess is a vertical slit in the coat which is closed by a metallic slide fastener. Here again the teeth of the fastener are externally protected by small fabric flaps and are internally concealed by a special tape sewed 10 to the inside of the coat.

The invention may be more fully understood from the following description taken in connection with the accompanying drawings wherein:

Fig. 1 is an exterior fragmentary view of part 15 of an overcoat with parts of the pocket and pocket flap broken away to disclose the slit and metallic fastener which closes it.

Fig. 2 is an interior view of the coat with part 20 of the interior protective flap for the "zipper" broken away for the sake of clearness.

Fig. 3 is a greatly enlarged and broken sectional view on the staggered line 3-3 of Fig. 1.

Fig. 4 is a view generally similar to Fig. 1 but 25 illustrating the form of invention in which the "zipper" is concealed under a flap at the rear edge of the pocket instead of being arranged within the pocket.

Fig. 5 is a view similar to Fig. 2 and showing 30 the inside of the coat illustrated in Fig. 4.

Fig. 6 is a greatly enlarged broken transverse 35 sectional view on the line 6-6 of Fig. 4.

Referring with particularity to the form of the invention shown in Figs. 1 to 3 of the drawings, "10" indicates the body of an overcoat at 35 the exterior of which a pocket is formed by sewing a patch "11" to the coat in conventional manner and preferably by sewing a pocket flap "12" to the coat so that it overlaps the open top of the pocket.

Within the pocket the body of the coat is provided with a diagonal slit extending from a point adjacent the upper forward corner of the pocket to a point well above the lower opposite rear corner. Sewed to the material upon opposite 45 sides of the slit as by lines of stitching "13" and "14" are fabric strips "15" carrying rows of metal teeth "16" adapted to be cammed into interengaging relationship by a slide element "17". The fabric strips "14" which carry the teeth are preferably provided with flap portions "18" which overlie the teeth at the inside of the pocket and the slide member "17" is provided 50 with an actuating chain "19" or an equivalent handle member disposed at the inside of the 55

pocket. Thus when the metallic seam or "zipper" is closed the teeth "16" on the pocket side of the coat will be fully covered by the flaps "18" and upon reaching the hand into the pocket it will 5 contact no metal with the exception of the slide member "17" or its handle "19".

In order to conceal the slide fastener at the interior of the coat and also to prevent this fastener from pinching or tearing the sack coat, 10 vest, or other garment beneath the coat I provide a protective flap "20". This flap overlies the otherwise exposed teeth of the metallic seam at the inside of the coat. It is somewhat longer than the seam and lines of stitching "21", "22" 15 secure one edge of the flap and also the ends of the flap to the coat. The flap will in no manner interfere with the insertion of the hand through the slit in the pocket when it is desirable to gain access to a sack coat pocket without unbuttoning the overcoat.

There are several advantages gained by making the slit in the pocket diagonal. In the first place, this is a natural angle for the hand and wrist to assume when the elbow is bent in reaching 25 for a sack coat pocket. The diagonal slit also prevents any appreciable sag in the fabric of the coat when the slit is opened, this in direct contradistinction to the sagging which would occur were the slit disposed horizontally. The 30 natural tendency of the slit to remain substantially closed even when the slide fastener is fully opened tends to prevent inadvertent loss of articles from the overcoat pocket.

The important point about terminating this 35 slit above the bottom of the pocket is the fact that cigarettes, matches and other small articles will not escape from the pocket even when the slit is fully opened.

I have described the application of this invention 40 to an overcoat but it will be readily apparent that it may be applied with equal facility to various types of coats or jackets particularly raincoats, windbreakers etc., which are customarily worn in inclement weather, and where it 45 may be desirable to gain access to the under-clothing without removing the hands from the pocket or unbuttoning the jacket or raincoat. The same thing applies to the general utility of the alternative form of invention shown in 50 Figs. 4 to 6 inclusive and which I shall now describe.

In this embodiment the slit which is closed by the slide fastener is not actually arranged within the pocket of the coat but is concealed by the 55 pocket.

Here "10a" represents the body of the coat, "11a" a pocket forming patch secured upon the exterior of the coat, and "12a" a flap to cover the open upper end of the pocket. One side of 60 the patch is sewed to the coat by a double line of stitching "21". The bottom of the patch is likewise sewed to the coat by a double line of stitching "22" but the opposite or rear side of the patch is sewed to the coat at the top and bottom only 65 by short lines of stitching "23". Lines of horizontal stitching "24" at the ends of the short lines of stitching "23" are connected by a vertical line of stitching "25" set inwardly at an appreciable distance and securing the patch to 70 the overcoat.

That portion of the patch between the lines of stitching "24" and "25" defines a flap "31" co-operating with the body of the coat to afford a concealed vertical recess open at its rear edge. 75 A vertical slit "26" extends lengthwise of this

recess and may be closed by a metallic seam or "zipper" construction of the same type as that illustrated in Figs. 1 to 3 inclusive. Tapes "27" secured by lines of stitching "28" to the body of the coat carry interengageable teeth "29" adapted to be cammed into interlocking engagement by a slide member "30", the latter carrying a chain or other handle "31" arranged exteriorly of the body of the coat and under the flap portion "31" of the patch. Here again the teeth 10 of the "zipper" are preferably exteriorly protected by small cloth flaps "32" and to prevent the teeth from being exposed at the inside of the coat as well as to prevent them from pinching or tearing the clothing under the coat, a special 15 protective flap "33" is sewed at both ends and along one side by lines of stitching "34" to the inner surface of the coat.

From the foregoing description it will be seen that with this form of construction no direct 20 communication between the pocket and the inside of the coat is afforded but that the pocket provides a naturally flat flap portion concealing the slit through which access may be had to sack coat pockets or other portions of the garments 25 which are worn under the coat. It will also be observed that the patch pocket at the outside of the coat is entirely conventional in appearance and the presence of the "zipper" closed slot 30 would not ordinarily be suspected. 30

In neither form of the invention do I alter the normal outside appearance of the coat, and the coats likewise appear of standard construction when viewed from the inside except for the small and more or less decorative flaps which 35 conceal the metallic teeth of the slide fastener.

It will thus be seen that there is herein described an article in which the several features of this invention are embodied, and which article in its action attains the various objects of the 40 invention and is well suited to meet the requirements of practical use.

As many changes could be made in the above construction, and many apparently widely different embodiments of this invention could be 45 made without departing from the scope thereof, it is intended that all matter contained in the above description or shown in the accompanying drawings shall be interpreted as illustrative and not in a limiting sense. 50

Having thus described my invention what I claim as new and desire to secure by Letters Patent is as follows:

1. As a new article of manufacture, a coat having an open topped pocket and a slit in the 55 coat providing access through the coat without opening the latter, a metallic seam comprising sets of interengaging teeth disposed at opposite sides of the slit and a slide member for engaging or disengaging the teeth, said slit being arranged within and concealed by the pocket of the coat. 60

2. As a new article of manufacture, a coat having a pocket and a slit in the coat concealed by said pocket and providing access through the coat without opening the latter, a metallic seam comprising sets of interengaging teeth disposed at opposite sides of the slit and a slide member for engaging or disengaging the teeth, said closable slit being disposed within the pocket of the coat and extending downwardly and rearwardly diagonally of the pocket, whereby it prevents sagging of the fabric of the coat when the slit is open. 65

3. A coat, jacket or the like having a patch pocket at the exterior thereof, a diagonal slit ar- 70 75

ranged in the coat and concealed by the pocket, a metallic slide fastener for closing the slit having the handle portion of its slide element arranged in the pocket and means secured to the inside of the coat for preventing contact between the slide fastener and the garment beneath the coat.

5 4. A coat, jacket or the like having a patch pocket at the exterior thereof, a diagonal slit arranged in the coat and concealed by the pocket, a metallic slide fastener for closing the slit having the handle portion of its slide element arranged in the pocket and means secured to the inside of the coat for preventing contact between the slide fastener and the garment beneath the coat, said diagonal slit extending from a point 10 near the upper forward corner of the pocket to a point above the rear lower corner thereof.

15 5. As a new article of manufacture a coat having a pocket and a slit in that portion of the coat which constitutes the inner wall of the pocket, the outer wall of the pocket concealing said slit and providing access through the coat without opening the coat, and separable fastener means accessible for manual manipulation 20 from the inside of the pocket for opening or closing said slit.

25 6. As a new article of manufacture a coat having a pocket and a slit in that portion of the coat which constitutes the inner wall of the pocket, the outer wall of the pocket concealing said slit and providing access through the coat without opening the coat, and separable fastener means accessible for manual manipulation from the inside of the pocket by opening or closing said 30 slit, said separable fastener means comprising sets of interengaging teeth disposed at opposite edges of the slit and a slide member disposed within the pocket for effecting engagement or disengagement of the teeth.

35 40 7. As a new article of manufacture a coat having a pocket and a slit in the coat concealed by said pocket and providing access through the coat without opening the latter, a metallic slide fastener for closing the slit including an operating device disposed within the pocket, a fabric flap secured at both ends and along one edge to the inner surface of the coat over the slide fastener, in such a fashion that it is not free to fold into

the slit when the latter is open and protects the clothing under the coat from being pinched by the slide fastener when the latter is being closed.

8. As a new article of manufacture a coat having a patch pocket, a slit in the coat concealed by the patch, a slide fastener also concealed by the patch for opening or closing the slit.

9. As a new article of manufacture a coat having a patch pocket, a slit in the coat concealed by the patch, a slide fastener also concealed by the patch for opening or closing the slit, and a protective strip sewed on the inner face of the coat in such a fashion that it does not tend to fold inwardly into the slit when the slit is open and prevents undergarments from being 10 pinched by the slide fastener when the latter is being closed.

15 10. A coat, a pocket forming patch secured to the exterior thereof, one edge portion of said patch being separated from the pocket proper 20 by a line of stitching and affording a flap co-operating with the coat to define a concealed recess at one edge of the pocket said coat having a slit therein concealed by said flap and a metallic slide fastener for closing the slit.

25 11. A coat, a pocket forming patch secured to the exterior thereof, one edge portion of said patch being separated from the pocket proper by a line of stitching and affording a flap co-operating with the coat to define a concealed 30 recess at one edge of the pocket said coat having a slit therein concealed by said flap and a metallic slide fastener for closing the slit said patch presenting the conventional external appearance 35 of a patch pocket and said flap being arranged at the rear edge of the pocket.

40 12. A coat, a pocket forming patch secured to the exterior thereof, one edge portion of said patch being separated from the pocket proper by a line of stitching and affording a flap co-operating with the coat to define a concealed recess at one edge of the pocket said coat having a slit 45 therein concealed by said flap and a metallic slide fastener for closing the slit, a flap secured to the inside of the coat and concealing the slide fastener and preventing contact therewith of garments under the coat.

JOSEPH SIEGEL.
